NESTABLE TABLE

Raphael Hodge, 1500 Noble Ave.,
Bronx, N.Y. 10460

Filed Oct. 9, 1973, Ser. No. 406,085

Term of patent 3½ years

Int. Cl. D6—03

U.S. CL. D6—27

FIG. 1 is a perspective view slightly in elevation of a nestable table showing my new design;

FIG. 2 is a side elevation view thereof;

FIG. 3 is a rear elevation view thereof; and

FIG. 4 is a bottom view thereof.

I claim:

The ornamental design for a nestable table, substantially as shown.
